COVERED TRIM PANEL AND METHOD OF
MANUFACTURING SAME

Paul R. Zinser, Detroit, Mich., assignor to Woodall
Industries Incorporated, Detroit, Mich., a cor-
poration of Michigan

Application September 25, 1933, Serial No. 699,959

8 Claims. (Cl. 154—2)

My invention relates to covered panels and particularly to automobile interior trim panels wherein the foundation of the panel is formed of suitable composition fibrous material and to an improved method of their manufacture. A suitable foundation board is one possessing thermoplastic characteristics whereby it may be stamped under heat and pressure to assume and retain an embossed configuration. One surface, which

10 surface is to be the exposed face of the finished panel, is covered with upholstery fabric or other suitable trim material.

An object is to provide such a panel wherein a foundation board is given an embossed design or bead and the covering material is so secured thereto that it is stretched taut over the embossment or bead formed in the foundation board and is so secured to the board along the base of the embossment or bead or outline that such embossment will stand out sharp and clear against the background of the covered panel and the fabric will be held securely against accidental detachment along the base of the embossment or bead.

25 It has heretofore been found that while finishing material such as any suitable trim fabric may be easily adhesively secured to the flat face of a panel board that it is difficult to securely fasten the same over an embossed surface and stretch it taut over the risers and embossments and then fasten it down securely along the base of such risers. When the material is stretched over the embossed surface there is a tendency for it to pull loose and become detached along the base 30 of the embossment. The stretching of the fabric taut places a strain thereon along the base of the embossment and it tends to loosen along such line. Loosening of the fabric along this line not only destroys the appearance of the design but 35 forms a line from which such loosening continues and increases to the ultimate impairment of the panel.

In accomplishing the object of my invention I propose to form a line of small spaced apart cavities along the base of the embossment or bead and to press the covering material into these cavities in such a manner that it is interlocked therein so that it will be interlocked at intervals along the base of the embossment over which it is 45 stretched and will be securely held within the interior of the foundation board against accidental detachment from the board.

It has also been found that this mechanical interlocking of the material at intervals along 50 the base of the embossment or bead may be so

handled as to constitute a decorative treatment of the board. I therefore propose to interlock the material at such intervals and in such a manner that the cavities into which it is depressed and interlocked will have the appearance of stitch apertures formed at the end of the individual stitches of a line of stitching. Through adopting this treatment the appearance of the covered panel is actually enhanced by the operation.

Other objects and advantages will more fully 10 appear from the following description, appended claims, and accompanying drawing, wherein:

Figure 1 is an elevation of a fragment of the interior of an automobile door showing a panel structure embodying my invention secured 15 thereto,

Figure 2 is an enlarged fragmentary elevation of a portion of the panel shown in Figure 1,

Figure 3 illustrates a cross section through a panel board with trim fabric secured thereto prior 20 to being treated according to the improved process embodying my invention, and

Figures 4 and 5 represent cross sections taken on lines 4—4 and 5—5 of Figure 2, respectively.

In carrying out my invention I employ a suitable 25 foundation board to serve as the foundation of a complete covered panel. This foundation board is formed of any suitable fibrous composition material possessing the desired characteristics. I prefer to employ a fibrous composition board 30 which possesses thermoplastic characteristics due to the presence of a thermoplastic binder and what is commercially known as KB board has been satisfactorily employed by me.

In the figures of the drawing this foundation 35 board is indicated as 10 and is provided on one surface with a suitable covering material such as fabric trim material indicated as 12. This trim material may be of any suitable woven or felted fabric or of any other character, such as 40 artificial leather or the like. In carrying out my invention the trim material is adhesively secured to one surface of the foundation board by a suitable adhesive as shown in Figure 3.

It has heretofore been proposed to emboss 45 such a covered panel board and the embossing or stamping operation is carried out in a die and under the heat and pressure of the die the foundation board assumes a deformed shape which it will retain upon cooling and holds the covering 50 material to such deformed shape. It has been found that in the stamping operation the covering material being drawn over the embossed portions of the board has a tendency to become loose along the juncture of the embossed portion with 55

the normal plane of the board or within depressions which may be formed therein as in bead work due to the stretching of the fabric and the tendency of the adhesive to loosen at these points of strain. It has heretofore been proposed to stitch the fabric along these points of strain but such stitching possesses disadvantages. The stitching weakens the interior structure of the panel board so that when the complete board is subjected to bending or other strain it has been found that there is a tendency to break along the line of stitching and such breakage in covered stitched panels always curl along the line of stitching. Furthermore, the stitching produces a series of perforations in the board which serve as entrance points for moisture to seep in to produce warping or other deformations which result from the entrance of moisture into a cellulose fibrous product unless the waterproofing characteristics of the product are such as to prevent such seepage.

I have found that the covering material may be securely held in place by so stamping the covered panel board as to produce a series of cavities or depressions 14 along the outline of the embossment into which the covering material is driven so as to be interlocked and securely held therein. These cavities are illustrated in Figures 4 and 5 where it will be noted that the covering material is driven into the cavities in the form of a fold and these cavities are spaced apart along the line of the bead which is indicated as 16. It is obvious that the cavities might be formed along the outline of any embossed design as well as a bead. Bead work is common practice and my illustration in connection with such a form is merely to exemplify the carrying out of my inventive idea. It will be noted that the forming of these cavities is carried out in the die in such a fashion that the board is not reduced in thickness at such point, a protuberance 18 being formed on the rear face of the panel board opposite each cavity representing a corresponding deformation of the structure.

To overcome any objection to this type of stamping the operation is so carried out as to simulate the appearance of stitching so that the treatment of the panel presents an appearance which is typical of a stitched panel without the disadvantages which attend the stitching of the panel. The covering material being driven into the small cavities is so adhesively secured by adhesive throughout the entire surface of the cavities and by being folded upon itself within this small space that it resists any tendency of the material to pull loose at this point of strain and the material is held securely throughout the entire face of the covered panel.

What I claim:

1. A trim panel comprising a panel board of fibrous thermoplastic material, covering material adhesively secured over one surface thereof, said panel board provided with an embossed design over which the covering material is stretched taut, said board provided along the base of said design with a plurality of small spaced apart cavities, said covering material being depressed and packed into said cavities and securely locked therein.

2. A trim panel comprising a panel board of composition fibrous material, flexible covering material adhesively secured over one surface of

the board, said board provided with an embossment over which the covering material is stretched taut, and provided along the base of said embossment with a series of small spaced apart cavities, said covering material being driven in the form of a fold into each of said cavities and interlocked therein. 5

3. A trim panel comprising a panel board of fibrous composition material, trim fabric material adhesively secured over one surface thereof, 10 said panel board provided with a bead embossed therein, and having a groove debossed in the board along the base of the bead, said trim fabric material being adhesively secured to the board along the base of the bead through being forced 15 into small cavities formed in the board in the bottom of the groove at spaced apart intervals.

4. That method of fabricating a trim panel and covering the same with fabric trim material comprising adhesively securing trim fabric material over one face of fibrous composition thermoplastic foundation board, stamping said covered panel board under heat and pressure producing an embossment therein and providing along the base of said embossment small spaced 25 apart cavities into which the trim fabric is driven and interlocked to hold the same securely along the base of the embossment. 20

5. That method of fabricating a trim panel and covering the same with fabric trim material comprising adhesively securing trim fabric material over one face of the fibrous composition thermoplastic foundation board, stamping said covered panel board under heat and pressure producing the bead therein and pressing the trim 30 fabric material into the structure of the foundation board at spaced apart intervals along the base of the bead to interlock the same into the bottom at such points. 35

6. A trim panel comprising a panel board of fibrous composition material, trim fabric material adhesively secured over one surface thereof, 40 said panel board provided with a bead embossed therein and having grooves debossed in the board along each side of the bead, the base of said 45 grooves being shaped with a plurality of small spaced apart cavities into which the trim fabric is driven into in folded formation to stretch the same in taut condition over the bead.

7. A trim panel comprising a panel board of fibrous thermoplastic material, fabric material covering one face of said panel, said panel board being shaped at spaced apart intervals along the base of said design to form a plurality of 50 small cavities in one face of the board each having a corresponding protuberance on the other face of the panel, said fabric material being driven deep into said cavities and interlocked with the thermoplastic board to stretch the fabric 55 taut over the embossed design. 60

8. The method of securing fabric material to an embossed fibrous composition panel over which the fabric is stretched which consists in producing during the embossing operation a series of small cavities in the bottoms of the grooves forming part of the embossed design, and driving the fabric material in the form of a fold into said cavities to interlock the same with the panel and to stretch the same in taut condition across the 65 embossed design. 70
